VARIABLE PITCH PROPELLER CONTROL

John Hays Hammond, Jr., Gloucester, and George
 A. Colley, Newton Center, Mass.; said Colley
 assignor to said Hammond

Application September 29, 1938, Serial No. 232,324

3 Claims. (Cl. 170—163)

This invention relates to variable pitch propellers and more specifically to means for automatically varying the pitch of a propeller so as to maintain the speed of a vessel constant under varying conditions of wind and weather.

The invention further relates to speed indicating means operated by the motion of the vessel through the water which directly controls means for varying the pitch of the propeller blades in such a way that the power supplied to the propeller is varied so as to maintain the vessel at a predetermined speed.

The invention also provides means for varying the rate of change of pitch of the propeller blades in accordance with the rate of change of the vessel's speed, thus preventing rapid changes of pitch of the propeller blades which might cause unnecessary strain and vibration on the driving machinery.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization, may be better understood by referring to the following description, taken in connection with the accompanying drawing forming a part thereof, in which the single figure illustrates diagrammatically the system as applied to the driving mechanism of a marine vessel.

In the following description and in the claims parts will be identified by specific names for convenience, but they are intended to be as generic in their application to similar parts as the art will permit.

Referring to the accompanying drawing, the hull of a marine vessel is indicated at 11. This vessel is driven by means of a propeller 12 which is provided with adjustable blades 13. The propeller 12 is attached to the end of a hollow shaft 15 which passes through an outboard bearing 16 and a thrust bearing 17. The shaft 15 is driven by a prime mover 20 which may be of any desired type and is preferably provided with a governor, nor shown, for maintaining a constant speed of rotation.

The blades 13 are connected to a variable pitch mechanism 18 which may be of any well known and standard construction such as that manufactured by the Escher-Wyss Company of Zurich, Switzerland, the details of which form

no part of the present invention and are accordingly not specifically set forth herein. This mechanism, in general, comprises a rod 19 slideable longitudinally within the shaft 15 and connected to control the pitch of the blades 13. The rod 19 is actuated by a piston 27 in a fluid pressure cylinder 27a. Fluid for actuating the piston 27 is supplied by a pump 26 through a control valve 25 and a distribution valve 25a which communicates with the cylinder 27a through ducts, not shown, in the shaft 15. A motor 21 rotates a worm 22 which operates to move the upper end of a floating lever 23, which, in turn, is pivoted to the end of a valve rod 24 which controls the valve 25. The piston 27 is connected by a rod 28 to a collar 29 which is slidably mounted on the shaft 15 and engages the lower end of the lever 23 so that the position of this end of the lever corresponds to the pitch of the blades 13.

The upper end of the lever 23 is connected by a wire 30 to an indicator 31 which shows the pitch at which the blades 13 are set. Stops 32 are provided for limiting the maximum and minimum pitch of the blades 13. The fluid pump 26 is driven either by a motor 33 or a belt 35 from the shaft 15. A reservoir 36 and a supply tank 37 are provided for the necessary fluid.

It is to be understood that other pitch control devices may be employed in place of that referred to above, for varying the pitch of the propeller blades 13 in response to actuation of the motor 21. A particular type is shown for purposes of illustration only.

Mounted on the hull 11 is a speed indicating device which may be of any well known and standard construction such as that made by the Kenyon Instrument Company of Boston and known as the Kenyon Speedometer. This comprises a strut 40 which is attached to a metallic bellows 41 containing fluid under pressure. The bellows 41 is connected by a hydraulic tube 42 to a speedometer 43, which is provided with a pointer 44 which registers with a scale 46 graduated in knots. It is to be understood that other types of speed indicating devices may be used if desired.

In accordance with the present invention means is provided to control the motor 21 in response to the position of the pointer 44. In the embodiment shown a contact 46 is attached to but insulated from the pointer 44. Surrounding the speedometer 43 and rotatably mounted thereon is a ring 47 to which is attached a segment of a worm gear 48. Meshing with the

gear 48 is a worm 49 which is rotated by means of a knurled knob 50. Mounted on but insulated from the ring 47 are a plurality of contact segments 51 to 56 which are selectively engaged by the contact 46.

The segments 51 and 56 are connected by flexible conductors to two conductors 60 and 61 which in turn are connected to reversing windings of the motor 21. The segments 52 and 53 are connected by flexible conductors to two resistors 66 and 67 the other ends of which are connected to the conductor 60. The segments 54 and 55 are connected by flexible conductors to two resistors 70 and 71 the other sides of which are connected to the conductor 61. The common lead of the reversing windings of the motor 21 is connected to one side of a battery 72 the other side of which is connected to the blade of a three position switch 73. The center contact of this switch is connected to the contact 46, the upper contact to the conductor 61 and the lower contact to the conductor 60.

Operation

In the operation of the form of the invention shown the pitch of the blades 13 is set at the normal operating angle for the speed at which it is desired to operate the vessel, which for example may be 20 knots. The setting of the propeller blades 13 is accomplished by moving the blade of the switch 73 into the upper or lower position which will cause the motor 21 to move the upper end of the lever 23 to the left or right to increase or decrease the pitch in a well known manner, the angle of pitch being indicated by the pointer of the indicator 31.

The vessel is then brought up to the desired speed as indicated by the pointer 44, in this case 20 knots. The ring 47 is then rotated by means of the knurled knob 50 until the insulation between the segments 53 and 54 engages the contact 46. The blade of the switch 73 is then moved into engagement with the center contact.

If the conditions under which the vessel is travelling should change such as encountering a strong head wind or running into a heavy sea and the speed of the vessel be thereby diminished, the strut 40 will receive less pressure so that the hydraulic cylinder 41 will transmit less pressure to the speedometer 43, the pointer 44 of which will therefore rotate in a counter clockwise direction to indicate a decrease of speed. The contact 46 will then engage the segment 54 and a circuit will be closed from the battery 72 through the resistor 70 to the motor 21 causing it to rotate slowly in a direction to move the upper end of the lever 23 to the left, for example. This will move the valve 24 to the left, which will allow fluid under pressure to pass from the pump 26 to the cylinder 27a by means of the ducts in the shaft 15. This will actuate the piston 27 which, by means of the rod 19 and the link mechanism, will cause the propeller blades 13 to slowly increase their pitch. This will cause more power to be transmitted from the prime mover 20, the R. P. M. being maintained constant by means of the governor, thereby increasing the speed of the vessel until it reaches 20 knots, at which time the contact 46 will again rest on the insulation between segments 53 and 54, thus stopping the motor 21.

If the vessel should increase its speed due to a following wind or other favorable conditions the reverse action would take place, thus causing

a gradual decrease in pitch of the propellers which would cause less power to be drawn from the prime mover 20, thus decreasing the speed until the contact 46 again rested on the insulation between the segments 53 and 54 at which time the motor 21 would stop.

If the changed conditions cause a rapid change of speed so that the contact 46 engages either segment 55 or 52 then resistor 71 or the resistor 66 will be thrown in circuit with the motor 21. As resistors 71 and 66 have less resistance than resistors 70 and 67 the motor 21 will be caused to rotate faster, thus changing the propeller pitch more rapidly to take care of the more rapidly changing conditions.

If the conditions change so quickly that the contact 46 engages either segment 51 or segment 56, then no resistance will be thrown in the circuit of the motor 21 and it will rotate at its maximum speed, thus changing the propeller pitch at a maximum rate. The stops 32 are provided so that the propeller pitch is prevented from exceeding certain limits beyond which it could not operate efficiently under any conditions.

In this way the pitch of the propeller blades 13 is varied to cause the propeller to operate so as to draw the required power from the prime mover 20 under the changed conditions to maintain the speed of the vessel constant. The rate of change of pitch will vary in accordance with the change of speed of the vessel so that with a gradual change of speed there will be a slow change of propeller pitch, thus preventing violent changes of pitch which would cause undue strain on the driving mechanism, disagreeable vibrations and inefficiency of the propeller.

Although only a few of the various forms in which this invention may be embodied have been shown herein, it is to be understood that the invention is not limited to any specific construction but may be embodied in various forms without departing from the spirit of the invention or the scope of the appended claims.

What is claimed is:

1. In a system for driving a vessel, a propeller having blades, means controlling the pitch of said blades, means responsive to the speed of travel of said vessel, a device actuated by said speed responsive means, said device being provided with a plurality of contacts which are adapted to be selectively closed in accordance with the direction and the amount of change in speed and control circuits associated with said contacts to actuate said pitch controlling means in a direction determined by the direction of change of said speed responsive means and at a rate determined by the amount of such change whereby the pitch is varied in a manner to maintain the vessel at a constant speed.
2. In a system for driving a vessel, a propeller having blades, means controlling the pitch of said blades, means of shiftable position responsive to the speed of travel of said vessel, means responsive to the direction of change of said speed responsive means connected to actuate said pitch changing means in a direction and by an amount to make a change in the pitch of said blades suitable for maintaining the speed of travel of said vessel constant, and means responsive to the amount of change of position of said speed responsive means in either direction to cause said pitch-changing means to operate at a rate of speed which varies according to said amount of change, being greater when the amount of said

change is greater and vice versa, whereby the rate of change of pitch of the propeller blades depends upon the amount of variation in speed of travel of said vessel.

3. In a system for driving a vessel, a propeller having blades, means controlling the pitch of said blades including an electric pitch-changing motor, means of shiftable position responsive to the speed of travel of said vessel, means responsive to the direction of change of said speed responsive means connected to actuate said pitch changing motor in a direction and by an amount to make a change in the pitch of said blades suit-

able for maintaining the speed of travel of said vessel constant, and means responsive to the amount of change of position of said speed responsive means to cause said pitch-changing motor to operate at a rate of speed which varies according to said amount of change, being greater when the amount of said change is greater and vice versa, whereby the rate of change of pitch of the propeller blades depends upon the amount of variation in speed of travel of said vessel.
